UNITED STATES PATENT OFFICE.

HUBERT KRANTZ, OF BROOKLYN, NEW YORK.

INCLOSED PANEL.

932,401.

Specification of Letters Patent. Patented Aug. 24, 1909.

Application filed April 4, 1906. Serial No. 309,728.

To all whom it may concern:

Be it known that I, HUBERT KRANTZ, residing at Brooklyn, in the county of Kings and State of New York, have invented certain new and useful Improvements in Inclosed Panels, of which the following is a full, clear, and exact description, such as will enable others skilled in the art to which it appertains to make and use the same.

10 This invention relates broadly to electrical switch-boards, but it more particularly concerns certain improvements and adaptations therein whereby the same will be rendered better adapted for practical needs.

15 This invention accordingly has in view, among other objects, the provision of an inclosed panel board so arranged and devised that a convenient access may be had to the operative features thereof for the purpose of renewing blown-out fuses and also for the purpose of affording a protection to an operator against the current during the throwing of the switch features.

Another object is to provide a switch 25 mechanism which, while arranged so as to be adapted for being actuated by any and all persons entitled to that privilege, still prevents such persons, who are frequently careless or inexperienced, from coming in contact with any current-carrying parts.

This invention eliminates the possibilities occurring in certain prior constructions whereby through careless operations short circuits may take place between the conductors, with the resultant fires, as well as accidental bodily injury to an operator. At the same time the construction is such that another person or persons, such as a regular electrician, may be provided with a key or otherwise be able to open the door without difficulty and be accordingly enabled to make repairs or adjustments to the inner details, and conversely unauthorized persons are prevented from having access 45 to such parts.

Another object is to provide an inclosed panel which will automatically designate, not only whether the switch is turned on or off, but will also indicate the location of lights controlled by the switch by means of name plates or the like on the face of the panel.

A further object is to provide an inclosed

panel board which, from an operative standpoint, will in usage possess a high degree of efficiency and effectiveness, and which structurally considered, will be of the greatest possible simplicity consonant with the ends to be attained, being composed of but few parts all adapted for being made at a minimum of cost and individually so formed as to be capable of being readily assembled in a neat and compact arrangement for accomplishing the purpose intended.

Other objects and advantages will be in part obvious and in part pointed out hereinafter.

With these and other ends in view, this invention accordingly consists in the features of construction, combination of parts and arrangement of elements hereinafter more explicitly set forth as an exemplification of the underlying principles involved in the invention.

In order that this invention may be more fully understood and be made comprehensible to others skilled in its relating arts, drawings illustrating a convenient means for carrying out the same are appended as a part of this specification, and while the controlling principle of the invention may be otherwise applied by modifications falling within the scope of the claims, the hereinafter disclosed embodiment is that which will ordinarily be preferable to employ in practice, and is regarded as representing substantial improvements over the many obvious or implied variations of the same. In such drawings it is to be noted that like numerals refer to corresponding parts throughout all the figures, of which:

Figure 1 is a sectional elevation showing details of the practical application of the invention. Fig. 2 is a modification showing the manner of employing a push-button switch, where the push-button only operates through the first protecting cover.

In carrying out this invention, it will be preferable to mount the details thereof within a suitable casing. Such part is designated by 1 and while the same may be of any suitable material, it is to be understood that in some cases it will be advisable to employ metal or suitable plastic material for the purpose. The casing is furthermore shown in the drawings as being continuous and free

from seams or joints and in this manner a superior protecting means is obtained. The shape and proportions of such casing will naturally be dependent upon the number, 5 size, and arrangement of the current-controlling features which may obviously be varied at will.

The current-controlling features which will presently be more specifically described, 10 are mounted within the said casing and removable covers provide for necessary access to the same. To this end a block 2 of suitable non-conducting material such as slate, 15 marble, porcelain or the like is arranged intermediate the current-conductors and the bottom of the casing. Such block will be provided at suitable intervals with recesses 3 within which retaining bolts 4 may be countersunk at their lower ends so as to be 20 out of contact with the casing and attached at their upper ends to suitable conductors positioned thereby.

The bus-bars 5, 6 and 7 are carried preferably upon the upper surface of block 2 and 25 are usually positioned intermediate the ends of the same as shown by the drawings. While the arrangement of the bus-bars is that employed in the ordinary three-wire system it will be understood that this invention 30 is not limited thereto as any suitable system may similarly be adapted to the same by the exercise of ordinary skill. The arrangement shown, however, is regarded as the preferable one and is believed to embody 35 substantial improvements over other arrangements.

Connected to the bus-bars in a suitable manner are a number of fuses and to more clearly explain the preferable manner of 40 making such connections a fuse 8 is shown in direct contact with bus-bar 5, whereas a fuse 9 is connected to bus-bar 6 by means of a suitable cross-bar 10 which is directly in contact with bus-bar 6 but is insulated from bus-bar 7 by a suitable member 11 which 45 may be of any non-conducting material. It will be seen that this arrangement is highly suitable for electrical work since the connections are made directly and all unnecessary 50 conducting pieces are obviated.

Leading from direct contact with the fuses are short conducting bars 12 and 13, the former having its contacting end slightly raised in accordance with the elevation of 55 the fuse 8 while the latter has its contacting end at a greater elevation in order to agree with the greater elevation of fuse 9 necessitated by the use of the insulating medium 11 on the bus-bar 7. These strips 12 and 13 60 each terminate through a partition 14 and are in direct contact with the terminals of suitable switches 15, which at their opposite terminals are in direct contact with short conductors 16, which may be provided with 65 suitable binding-posts 17 for affording a

convenient connection to the branch line circuits. A partition 18 determines the extent of the space within which the switch is located and may be conveniently positioned upon the block 2.

A flush cover is provided for the switch chamber or space and preferably comprises a plate 19, which has a suitable aperture for the passage of a switch-controlling member and such plate may be conveniently mounted 75 and positioned by means of suitably disposed straps 20 which have down-turned ends 21 and are positioned with respect to the side walls 14 and 18 by means of screws 22. The plate 19 is preferably affixed to the straps 80 through small screws or bolts 23 which are flush with the exposed surface of the plate. By this means a very serviceable expedient is obtained and the whole possesses a neat and attractive appearance. 85

The parts thus described are preferably concealed from view by hinged covers 24 which are preferably pivoted at a point 25 or otherwise so arranged that they may be removed to disclose the underlying parts. 90 As the operation of the switch will be more frequent than the necessity for replenishing the fuses or making repairs, this invention provides in that part of the cover overlying the switch an aperture 26 through which access may be had to said switch. As ordinarily the switch will be provided with a protruding rotary shaft 27, the aperture will be lined by a bushing such as has been designated by 28 on the drawings. Preferably 100 the revoluble shaft 27 terminates intermediate the inner and outer ends of the bushing and is provided with an end adapted to be engaged by a suitable actuating wrench or key. A convenient form for the purpose is 105 that shown on the drawings and consists of a suitable tongue 29. It will be understood that while the switch is shown with a revoluble shaft protruding through the protecting cover as well as the door, such shaft 110 may be wholly or partially dispensed with and in lieu thereof a separable key may be provided and adapted for being passed through the outer door and the inner flush cover. 115

In carrying out this invention, details of construction may be varied from those shown, and yet the essence of the invention be retained; some parts might be employed without others, and new features thereof 120 might be combined with elements old in the art in diverse ways, although the herein described type is regarded as embodying substantial improvements over such modifications. 125

As many changes could be made in the above construction, and many apparently widely different embodiments of the invention could be made without departing from the scope thereof, it is intended that all mat- 130

ter contained in the above description or shown in the accompanying drawings shall be interpreted in an illustrative and not in a limiting sense.

5 It is furthermore desired to be understood that the language used in the following claims is intended to cover all the generic and specific features of the invention herein described, and all statements of the scope of 10 the invention which as a matter of language might be said to fall therebetween.

Having described my invention, what I claim as new and desire to secure by Letters Patent is:—

15 1. In a device of the class described, an inclosed chamber having a perforate fixed cover, a switch within said chamber and provided with actuating means underlying said opening, main and branch line terminals extending into suitable contact with said switch, and an outer cover arranged to normally conceal said perforate cover and provided with one or more apertures in registry with said perforations.

20 2. In a device of the class described, an enlarged casing an inclosed chamber having a perforate fixed cover positioned within said enlarged casing, a switch within said chamber and provided with actuating means 25 underlying said opening, main and branch line terminals extending into suitable contact with said switch, and an outer cover arranged to normally conceal said perforate cover and provided with one or more apertures in registry with said perforations.

30 3. In a device of the class described, a casing, a block mounted on the bottom thereof, a perforate fixed cover mounted on said block, a switch within said chamber and 35 provided with actuating means underlying said opening, main and branch line terminals extending into suitable contact with said switch, and an outer cover arranged to normally conceal said perforate cover and provided with one or more apertures in registry with said perforations.

40 4. In a device of the class described, an inclosed chamber having a perforate fixed cover, a switch within said chamber and 45 provided with actuating means extending through the perforations in said cover, main and branch line terminals in electrical connection with said switch, and an outer cover adapted to be actuated to afford access to 50 said parts, said cover being provided with one or more apertures through which said switch may be actuated said apertures in the outer cover being in registry with those in the inner perforate cover.

55 5. In a device of the class described, an inclosed chamber having a perforate fixed cover, an outer cover arranged to normally conceal said perforate cover, said outer cover being provided with apertures in registry 60 with those in the perforate cover, and a

switch within said chamber and provided with actuating means extending into said perforations.

6. In a device of the class described, a casing, a block of insulating material within 70 said casing and attached to the inner rear face thereof, a pair of side walls rising from each end of said block and forming switch-inclosing chambers, said chambers being spaced away from the side walls of said 75 casing, main line conductors mounted upon said block intermediate said chambers, a switch located within each of said chambers and arranged in electrical connection with said main line conductors, and a hinged 80 cover arranged on said casing to normally conceal the features therein, said cover being provided with apertures through which said switches may be actuated.

7. In a device of the class described, an 85 inclosed chamber, a cover hinged to a suitable support and provided with a suitable aperture, a bushing in said aperture, and a switch within said chamber and providing a rotary shaft extending into said bushed 90 aperture and adapted to be turned therein about a longitudinal axis, whereby said switch may be opened and closed.

8. In a device of the class described, a casing, a chamber positioned therein intermediate the side walls thereof, an inner cover supported by the sides of said chamber and having a perforation, a switch within said chamber having an actuating means extending through said perforation, and an outer 100 cover hinged to said casing and normally resting upon the walls of said chamber, said cover having an aperture through which said means may be operated.

9. In a device of the class described, a casing, a block of insulating material affixed to the rear inner face of said casing, said block terminating at a distance from the side walls of said casing, a chamber mounted upon said block at each end thereof, main line conductors mounted on said block intermediate said chambers, a switch located within each of said chambers and arranged in electrical connection with said main line conductors, and a hinged cover arranged on said casing 110 to normally conceal the features therein, said cover being provided with apertures through which said switches may be actuated.

10. In a device of the class described, a casing, a block of insulating material within 120 said casing, and attached to the rear inner face thereof, a pair of walls rising from each end of said block and forming switch-inclosing chambers, said chambers being spaced away from the side walls of said casing, 125 main line conductors mounted upon said block intermediate said chambers, a switch located within each of said chambers, conductors leading from said main line conductors and terminating in electrical con- 130

nection with said switches, an inner plate covering each of said chambers and having an aperture, switch-actuating means protruding through said apertures, and a hinged 5 cover arranged on said casing, said cover being provided with bushed apertures through which said switches may be actuated.

11. In a device of the class described, a casing, a block affixed to the rear inner face 10 thereof and terminating at a distance from the side walls of said casing, main line conductors carried by said block intermediate the ends thereof, fuse-plugs connected to appropriate conductors, laterally-extending 15 conductors leading from said fuse-plugs, switches mounted upon said block adjacent the ends thereof and in electrical connection with said lateral conductors, side walls enclosing said switches, plates carried by said 20 side walls and overlying said switches, said plates having suitable apertures, a switch-actuating means extending through said aperture, and a hinged cover carried by said casing and arranged to normally conceal the 25 features therein.

12. In a device of the class described, a casing, a block of insulating material within 30 said casing and attached to the inner rear face thereof, a pair of side walls rising from each end of said block and forming switch-inclosing chambers, said chambers being spaced away from the side walls of said casing, main line conductors mounted upon said 35 block intermediate said chambers, a switch located within each of said chambers and arranged in electrical connection with said main line conductors, and a displaceable cover arranged on said casing to normally conceal the features therein, said cover being provided with apertures through which 40 said switches may be actuated.

13. In a device of the class described, an 45 inclosed chamber, a cover displaceably mounted thereon and provided with a suitable aperture, a bushing in said aperture, and a switch within said chamber and providing a rotary shaft extending into said bushed aperture and adapted to be turned therein about a longitudinal axis, whereby 50 said switch may be opened and closed.

14. In a device of the class described, a casing, a chamber positioned therein intermediate the side walls thereof, an inner 55 cover supported by the sides of said chamber and having a perforation, a switch within said chamber having an actuating means extending through said perforation, and an outer cover detachably mounted on said casing and normally resting upon the walls of

said chamber, said cover having an aperture 60 through which said means may be operated.

15. In a device of the class described, a casing, a block of insulating material affixed to the rear inner face of said casing, said block terminating at a distance from the 65 side walls of said casing, a chamber mounted upon said block at each end thereof, main line conductors mounted on said block intermediate said chambers, a switch located within each of said chambers and arranged in 70 electrical connection with said main line conductors, and a displaceably mounted cover arranged on said casing to normally conceal the features therein, said cover being provided with apertures through which 75 said switches may be actuated.

16. In a device of the class described, a casing, a block of insulating material within 80 said casing and attached to the inner rear face thereof, a pair of walls rising from each end of said block and forming switch-inclosing chambers, said chambers being spaced away from the side walls of said casing, main line conductors mounted upon said 85 block intermediate said chambers, a switch located within each of said chambers, conductors leading from said main line conductors and terminating in electrical connection with said switches, an inner plate covering 90 each of said chambers and having an aperture, switch-actuating means protruding through said apertures, and a displaceably mounted cover arranged on said casing, said cover being provided with bushed apertures 95 through which said switches may be actuated.

17. In a device of the class described, a casing, a block of insulating material within 100 the casing, a pair of walls rising from one end of the block, and forming a switch inclosing chamber, a switch within said chamber, a removable cover for the switch chamber having one or more apertures in line with the switch for the operation thereof.

18. In a device of the class described, a 105 casing, a block of insulating material within the casing, a pair of walls arising at one end of the block and forming a switch inclosing chamber, a switch within said chamber, a removable cover for the switch chamber, having 110 an opening in line with the switch.

In testimony whereof I affix my signature, in the presence of two witnesses.

HUBERT KRANTZ.
